UNITED STATES PATENT OFFICE.

ABRAHAM COLLEY, OF SOUTH RICHMOND, VICTORIA.

CARTRIDGE - MAGAZINE ATTACHMENT FOR RIFLES.

SPECIFICATION forming part of Letters Patent No. 413,032, dated October 15, 1889.

Application filed April 24, 1888. Serial No. 271,748. (No model.) Patented in Victoria July 27, 1887, No. 5,205; in New South Wales March 9, 1888, No. 538; in Tasmania March 13, 1888, No. 550/10; in South Australia March 13, 1888, No. 984; in New Zealand March 19, 1888, No. 2,870; in England April 12, 1888, No. 5,471; in Belgium April 14, 1888; in India June 12, 1888, No. 820, and in Queensland November 2, 1888, No. 502.

To all whom it may concern:

Be it known that I, ABRAHAM COLLEY, a subject of the Queen of Great Britain, residing at No. 88 Green Street, South Richmond, in the British Colony of Victoria, armorer to the government of the said colony, have invented a new and useful Improved Cartridge-Magazine for Attachment to Certain Descriptions of Rifles, (for which I filed an application for Letters Patent in the British Colony of Victoria aforesaid, dated the 27th day of July, 1887, and numbered 5,205; in Great Britain, dated April 12, 1888, No. 5,471; in Belgium April 14, 1888, not numbered; in New South Wales, dated March 9, 1888, No. 538; in Tasmania, dated March 13, 1888, No. 550/10; in South Australia, dated March 13, 1888, No. 984; in New Zealand, dated March 19, 1888, No. 2,870; in Queensland, dated November 2, 1888, No. 502, and in India, dated June 12, 1888, No. 820,) of which the following is a specification.

This invention consists of an improved cartridge-magazine for attachment to those descriptions of rifles which have a falling block for receiving cartridges as they are discharged from my magazine. The Martini-Henry rifle is of such a character, and is the one to which my magazine is primarily designed to be attached. It consists of a steel box approximating in plan to the shape of a cartridge when laid horizontally—that is to say, one end of the magazine is made wider than the other, the wider end being for the butt-end of the cartridge. It may be made as high as is convenient, the cartridges being laid one on the top of the other, and, if preferred, there may be a second vertical row of cartridges to discharge into the first row; but I think one row will be most convenient and will be generally adopted. I affix a vertical strip of metal on each of the inner sides of the magazine just at the point where the butt-end of the cartridge decreases in size, so as to act as a guide, and thus prevent their jamming. In the lower part of this magazine I provide a spring-cradle, in which the lowermost cartridge rests, and I preserve this cradle in position by means of a spiral spring attached to one end of the spindle which carries such

cradle, and I attach a thumb-crank on the end of such spindle and outside the magazine, by moving which toward the rifle to which the magazine is attached the lowermost cartridge—that is to say, that which is immediately resting on the cradle—is discharged through a long slot reaching from end to end of the magazine, and when this magazine is properly attached to a Martini-Henry rifle the said cartridge just falls into the falling block made for the purpose.

In order to firmly attach this magazine to the rifle, I make a dovetailed slot immediately below the cartridge-discharge opening to enable the magazine to be slid onto a corresponding male dovetail, which I firmly affix to the side of the rifle. When thus slid onto this dovetailed piece, I preserve it in position by a spring-catch. The cartridges are supplied to the magazine through a door at its broad end, which is held in position by another spring-catch.

In order, however, that my invention may be clearly understood, I will now proceed to describe the drawings hereto attached, which clearly illustrate my magazine and the mode of its attachment to a Martini-Henry rifle.

Figure 1 shows a plan and Fig. 2 a side elevation of my magazine attached to a Martini-Henry rifle. Fig. 3 is an elevation of the opposite side to that shown in Fig. 2. Fig. 4 is a back end elevation of same with the magazine-door open. Fig. 5 is a plan of spring for securing magazine to body of rifle. Fig. 6 is an elevation of same. Fig. 7 is a section on line $x x$ of Fig. 2, and Fig. 8 is an isometric view of the magazine-ejector.

A is the magazine itself, having a door A', fastened by a spring-catch A².

B is the cradle upon which the cartridges rest. B' is the spindle of such cradle, which is made hollow and has a smaller square spindle running through it. It is fastened in position by a collar and pin B². At its rear end is a coiled spring B³, and on its rear extremity is a thumb-crank B⁴.

C is a dovetailed slot fitting onto a corresponding dovetailed bar C', fitted onto the side of the rifle.

C² is a spring-catch for preventing the mag-

azine from slipping when the dovetailed slot is slid over the dovetailed bar.

C³ is a thumb-piece for pressing said spring-catch out of position when it is desired to remove the magazine from the rifle.

D is the ordinary falling block on the top of a Martini-Henry rifle, and it is evident that my invention is applicable to any other rifle which has a similar falling block for receiving the cartridges as they are discharged one by one from my magazine.

The mode of operation is as follows: The door A' of the magazine is first opened and the cartridges supplied one above the other, the butt-ends hindmost, as clearly shown in the drawings. The door is then shut and the magazine attached to a rifle by sliding the dovetailed slot C over the dovetailed piece C', affixed to the rifle. It is then ready for firing. Immediately one cartridge has been discharged its empty casing is thrown upward in the ordinary way, and by a simple quarter-turn or less than a quarter-turn of the thumb-crank B⁴ the lowermost cartridge—that is to say, that one which immediately rests on the cradle B—is discharged through the slot E into a receptacle D on the top of the rifle. This can be then fired and the operation repeated until the magazine is empty, when of course it must be recharged.

I have shown a magazine containing five cartridges; but there is no reason except that of convenience why it should not be made to carry more or less. I think, however, a magazine of the size I have shown will be that which will be most generally adopted.

Having thus described the nature of my said invention and the manner of perform-

ing same, I hereby declare that what I claim as new and of my invention is—

40

1. The herein-described magazine, consisting of the case or box A, provided with the end-gate A', a lock for said gate, a discharge-slot E in its side wall, a dovetailed groove below said slot, and a spring-latch C', whose hook 45 end C² projects into the groove, substantially as described, for the purposes specified.

2. In a magazine-gun in which the magazine is applied to one side of the receiver, the combination, with said receiver, of a magazine provided with a discharge-opening of less diameter at the forward than at the rear end, and an ejector consisting of a revoluble shaft and two saddles mounted thereon, having horns of unequal length, and operating 55 to support the lowermost cartridge and eject the same into the receiver and hold the next succeeding cartridge against downward motion, substantially as described.

3. The herein-described magazine, consisting of the case or box A, provided with the end-gate A', a lock for said gate, a discharge-slot E in its side wall, a dovetailed groove below said slot, and a spring-latch C', whose locking-hook C² projects into said groove, and 65 which is provided with the thumb-piece C³, in combination with an ejector consisting of a revoluble shaft, two saddles B, having horns of unequal length, mounted on said shaft, and a spring for returning the ejector into its 70 normal position when moved out of it, substantially as and for the purposes specified.

ABRAHAM COLLEY.
